UNITED STATES PATENT OFFICE

GEORGE L. MARKLEY, OF CULVER CITY, CALIFORNIA

WASHING-MACHINE IMPELLER

Application filed March 22, 1927. Serial No. 177,310.

This invention relates to a washing machine, especially adapted for textiles, fabrics and like articles, although useful for other purposes wherein it is desirable to have currents of water play over articles submerged therein. The present invention is especially suitable for embodiment in domestic washing machines, although in no manner limited to such use. It appertains to a washing machine comprising a container for the washing liquid, such as water, and an agitator having blades operating upon the fluid to cause currents therein which have components of movement outwardly and peripherally. Broadly, such washers are well known, as it is common to provide an upright shaft within the container and an agitator with blades. A channel for the articles to be washed is thereby provided between the shaft and the wall of the container. However, the currents produced by such agitators tend to move the articles toward and maintain them in position at the shaft, thereby causing them to become entangled about the shaft and with each other, subjecting them to possible injury and damage and militating against efficient speedy washing.

The primary object of this invention is to provide a washing machine having an impeller arranged to create currents which leave the articles and tend to maintain them at a distance from the shaft. Another object of this invention is to provide an impeller which will entrain air in the liquid, whip the same and thereby distribute the soap or like materials thoroughly throughout the liquid, and in the case of soap quickly form suds. A still further object of this invention is to provide a combination of an impeller and a hood to aid in producing suds and also to serve as a protector for delicate fabrics and textiles which it may be desired to wash.

These objects together with other objects and corresponding accomplishments are obtained by means of the embodiment of my invention illustrated in the accompanying drawing, in which:

Fig. 1 is an elevation of portions of the machine essential to the present invention, with a part of the container broken up to

better illustrate the impeller construction; Fig. 2 is a plan view; Fig. 3 is a perspective view of one form of my impeller detached from the agitator; and Fig. 4 is a hood for the impeller.

I have shown herein my invention embodied in an attachment which may be mounted upon a standard type of agitator. It will be understood however, that the invention is in no manner limited to the specific construction shown. The specific details of the structure shown herein are for illustrative purposes only. Variations of the structure will be apparent to those skilled in the art as the description proceeds.

In Fig. 1, a container 10 is shown which may be of the cylindrical tub type. Upstanding through the center thereof is a shaft 11 upon which is mounted an agitator 12. In the particular construction shown, this agitator comprises a disk like bottom plate with a stream line anticline toward the center and having radially extending wings 13 on one side. The shaft is preferably oscillated by motor mechanism not shown, water being placed within the container to about the level indicated by the dotted line. The water or washing liquid is projected radially outward by the wings 13, impinging upon the peripheral wall of the container and then spreading, most of it upwardly, back toward the shaft and then downwardly. This would tend to carry fabrics and the like articles upwardly and against the shaft. Various types of agitators are made, some having the disk portion above the wings. However, my invention is in no manner limited to any particular agitator construction or even use therewith.

Mounted over the shaft 11 is my improved impeller comprising a tubular portion 14 which snugly fits over the shaft and is provided with blades 15 of triangular form. In the present instance, the lower edges of the blades are provided with channels as indicated by 16 for the purpose of straddling the agitator wings and seating thereon. This particular structure aids in holding the impeller in position upon the shaft. In the blades 15 are perforations 17, preferably dis-

tributed over the face thereof. The size and location of the perforations may be arranged as it is found expedient. An impeller so constructed forms a detachable unit.

5 With my improved impeller mounted on the agitator, the operation is as follows:

Oscillation or rotation of the shaft will cause currents of water or liquid to be started outwardly. However, due to the variation 10 in radial extent of the blade from top to bottom, the current flow will be greatest at the bottom of the container and least at the top there being a gradual increase in current strength from top to bottom of the blades.

15 This causes a vortex action, the liquid moving outwardly at the bottom, then toward the top and inwardly toward the shaft and then down to the bottom plate being directed by 20 its stream line surface outwardly. The tendency to move the article toward the shaft will be well distributed over the outer edge of the impeller. There is also a current downwardly adjacent the shaft which tends to move the articles downwardly, and, if they are in contact 25 with the edges of the blades, they will be moved outwardly due to the inclination of the outer edges. The holes in the blades will tend to whip the liquid and thoroughly stir the same. The agitation of the water is such 30 that close to the impeller blades bubbles are formed which pass downwardly from the upper surface, air being entrained and aiding in the washing action. To further aid in preventing articles from wrapping about the 35 impeller, rollers 18 are journaled at the edges of the impellers thereby providing anti-friction means for contacting with the articles being washed.

In Fig. 4, a hood 19 is shown which may 40 be slipped over the impeller, encompassing the same. This hood is formed by a shell and has perforations 20 through which the liquid may pass. Rollers 21 are journaled on the shell and are placed to provide means 45 for the articles to roll over without friction. The construction is such that the hood may be placed over the impeller, and any fabrics or garments within the channel between the impeller and the wall of the container will be 50 protected from contact with the blades. Furthermore, there is a somewhat violent agitation of the liquid at the blades and within 55 the hood. Soap or washing fluid which may be added are thoroughly mixed and agitated, especially within the hood. In the case of soap, suds are quickly formed.

It will be obvious that the impeller may be 60 constructed as a unit to form a combined agitator and impeller or a single impeller. The 65 impeller as an attachment may be built for mounting upon various standard types of agitators, and its mechanical construction will be varied accordingly.

What I claim is:

65 1. In a washer, a container, an operating

shaft extending therein, impeller blades secured to said shaft extending outwardly therefrom and ending short of the peripheral wall of said container so as to provide a channel for the articles to be washed, said blades having perforations extending therethrough, and a shell having perforations detachably mounted over said impeller blades.

2. In a washing machine, a container, an upright operating shaft therein, an agitator having radially extending wings, and an impeller including perforate blades arranged to be mounted over said shaft and seated on said wings.

3. In a washer, a container, an upright operating shaft therein, an agitator having radially extending wings, an impeller including perforate blades arranged to be mounted over said shaft and seated on said wings, said blades being of triangular form with the bases thereof arranged to straddle said agitator blades.

4. In a washer, a container, an upright operating shaft therein, impeller blades secured to said shaft, and a perforate shell detachably disposed over, housing and secured to said blades so as to be rotatable by the latter.

In witness that I claim the foregoing I have hereunto subscribed my name this 16th day of March, 1927.

GEORGE L. MARKLEY.
